(57) **CLAIM**

The ornamental design for a rear end of an electrically heated tank for an asphalt distributor, as shown and described.

DESCRIPTION

FIG. 1 is a rear-right-elevated perspective view of a rear end of an electrically heated tank for an asphalt distributor showing my new design;

FIG. 2 is a rear-right-bottom perspective view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed lines depict portions of the tank that form no part of the claimed design. The appearance of any portion of the tank between break lines forms no part of the claimed design.

1 Claim, 4 Drawing Sheets
